STEAM GENERATOR WITH FORCED PASSAGE OF THE OPERATING MEDIUM

Martin Eule, Berlin-Spandau, Germany, assignor to Siemens-Schuckertwerke Aktiengesellschaft, Berlin-Siemensstadt, Germany, a corporation of Germany

Application March 12, 1937, Serial No. 130,477
In Germany November 23, 1934

3 Claims. (Cl. 122—448)

My invention relates to steam generators of the forced-flow tubular type and it has for an object to provide a control system therefor wherein effects of lag, so far as the temperature impulse is concerned, are substantially avoided. This application is a continuation in part of application Serial No. 50,860, filed by me on November 21, 1935 for Steam generators with forced passage of the operating medium.

10 A further and more particular object of my invention is to modify the steam-producing conditions of one of the tubes of a plurality of parallel-connected tubes so that said tube will have a region of variable temperature overlapping a portion of the evaporation zone of the remaining tubes, or within the physical limits of the latter, whereby there is provided a tube region of variable temperature within the main evaporation zone and which region may be used 20 to provide a temperature impulse for the controlling apparatus.

In steam generators of the above character, the supply of the operating medium and the fuel must be varied in such a manner as to approximately maintain a predetermined ratio of both operating media, if in the case of variations of load the condition of the steam produced is to remain unchanged. This may be also accomplished by the two regulating methods which, 30 as a rule, have hitherto been employed. By one of the regulating methods the operating medium and the fuel is simultaneously supplied in a greater or smaller amount depending upon the desired output, in which case a correction impulse is caused to be transmitted in response to the steam temperature for ensuring a reliable regulation thereof, which impulse in addition acts upon the supply of fuel. According to the other method the supply of the operating medium and the fuel is not varied simultaneously, but in succession; that is to say, the supply of the operating medium is at first adjusted to the desired new value and then the supply of fuel is regulated by an impulse derived in response 40 to a variation of the temperature of the steam produced. In both regulating methods, the derivation of an impulse in response to the temperature of the steam produced plays an important part. For the transmission of this temperature impulse only two points of the heating surface of the steam generator had hitherto been taken into consideration; viz. the superheater and the preheater. The derivation of the impulse from these parts of the heating surface is, however, not fully satisfactory. An impulse derived from

the superheater arrives, as a rule, too late. The regulation effected by this impulse, consequently, lags considerably, whereas the derivation of the impulse at the preheater is effected so prematurely that considerable variations of the operating conditions may again occur at the end of the generator. No temperature impulse may be derived from the part of the heating surface lying between the preheater and the superheater; i. e., from the evaporating heating surface of the 10 generator, since the temperature of the operating medium during the evaporation remains unaltered.

The object of the present invention is, therefore, to utilize the part of the heating surface 15 lying between the preheater and the superheater for the transmission of the impulse.

The essence of the invention consists in general in the fact that the supply of heat or of the operating medium to one of the tubes connected in parallel and forming the heating surface is so regulated with respect to the other tubes that in this particular tube the preheating terminates later or the superheating begins earlier than in the other tubes and that the temperature impulse is derived from this tube from a point where the preheating terminates or the superheating begins.

If the impulse in response to the temperature of the superheated steam is to be transmitted 30 in due time, the tube destined for the supply of the impulse must experience with respect to the other tubes a decreased supply of the operating medium or an increased supply of heat. Depending upon the extent, to which the decrease or 35 increase of the supply of both mentioned operating media is brought about, the superheating in the tube supplying the impulse, measured according to the length of the tube, will commence correspondingly earlier than in the other tubes. 40 It is thus possible to derive the temperature impulses to a sufficient extent from a heating surface part which normally forms the evaporating heating surface. In practice, this may be accomplished in the simplest manner by reducing 45 the supply of operating medium to the measuring tube with respect to the other tubes. In this case, it is only necessary to insert in this tube in the path of flow at a suitable point, preferably in the zone in which the operating medium is 50 still liquid, a resistance correspondingly rated. Dependent upon the magnitude of this resistance, the point at which the superheating begins, will displace itself in the measuring tube more or less opposite to the direction of flow of the 55

operating medium with respect to the other tubes.

It has hitherto been customary in steam generators with forced passage of the operating medium to arrange at least one part of the heating surface, in which under normal operation the conversion of liquid into steam is effected, as contact heating surface in the path of the fuel in order to prevent a burning out of the tubes due principally in this phase of production of steam to salts depositing from the operating medium. Since, with a measuring tube having means providing for its superheating zone being displaced forwardly relatively to the superheating zone of the other tubes, the other phases or zones of steam production of the measuring tube are also displaced to more or less extent in the direction opposite to flow of working fluid, with the result that the salt deposit zone of the measuring tube may not remain within the contact or convection heating region of the generator but be shifted into the radiant heat zones; and, in consequence, it may happen that the measuring tube, because of the wandering of the phases of steam production and creeping of the salt deposit zone into the radiant heat zone, or zone of high heat intensity, may have salt deposited in portions of the surface thereof subject to such high temperatures and give rise to burning out of the measuring tube, this objection having already been avoided by the intentional displacement of the salt deposit zone of the remaining tubes into the contact or convection heating surface where such a relatively low temperature normally obtains as to avoid burning out of tubes, even though deposits of salt should occur.

The other solution, as above generally stated, of the problem upon which the invention is based prescribes that at least one of the parallel connected tubes should experience an increased supply of operating medium or decreased supply of heat with respect to the other tubes and that the temperature impulse should be derived from this particular tube at the point, at which the preheating ends.

It may be further stated that the invention has a particular importance for such steam generators which are fed with an excess of operating medium, and in which the steam before the beginning of its superheating flows into a drum, in which the excess of water is separated from the steam produced up to that moment and is carried off from the generator. For such steam generators it was hitherto not possible to derive for the boiler a temperature impulse suitable for regulating purposes before the separating drum. If the invention is to be applied for these steam generators two methods are possible according to the invention. In accordance with one method, the preheating zone is displaced, as above described, toward the boiler outlet, that is, in this case, toward the separating drum, and the temperature impulse is taken at a point along the measuring tube within the final region of the preheating zone of the measuring tube which overlaps the initial portion of the evaporation zone of the remaining tubes. In the other method, the measuring tube is so arranged and steam-producing media are so supplied thereto that the initial portion of the superheating zone thereof overlaps a portion of the evaporation zone of the remaining tubes; and, as before, the initial overlapping portion of the superheating zone of the measuring tube is used to give a temperature impulse for controlling purposes. The tempera-

ture impulse necessary for the regulation of the generator may be then derived from this heating surface point, at which the superheating begins. It suffices if the supply of the operating medium or the supply of heat for this measuring tube is so regulated that the steam flowing from this tube into the salt separating drum is only slightly superheated.

Thus, it will be seen that, in all applications of the invention, a plurality of parallel tubes are arranged to have at least one thereof serve as a measuring tube in order to provide a controlling temperature impulse so that lag may be minimized. Any suitable means may be employed to secure offsetting of the zones of steam production of the measuring tube with respect to such zones of the remaining tubes, the essential feature being to provide for the temperature impulse being taken at a point of variable temperature along the measuring tube and falling within the physical limits of the evaporation zone of the remaining tubes.

In the drawings, Figs. 1 to 5, inclusive, are diagrammatic views illustrating the essential feature or characteristic of the present invention;

Fig. 6 is a diagrammatic view showing the application of the principle of Figs. 1, 3, and 5;

Fig. 7 is a diagrammatic view showing the application of the principle of Figs. 2 and 4.

Figs. 8 and 9 are diagrammatical sectional views of flow control or throttling devices for the tubes.

The present invention is illustrated in diagrammatic form in Figs. 1 to 5. The tubes forming the heating surfaces are diagrammatically represented in the form of heavy lines. The ends of the tubes enter collecting or distributing vessels. The direction of flow of the operating medium is indicated by the arrows as shown. Flow control or throttle points in the tubes are indicated by cross lines intersecting the tubes, whereas the temperature points are indicated by small circles drawn on the tube lines. Insofar as the flow control or throttle points are cut off or the temperature measuring points are not used for the regulation the corresponding symbols are shown in all figures in dashes. In all figures the lowest of the three tubes serves for the reception of the impulse which as above described may alternately be derived from the one or the other of the tubes shown by the use of change-over devices not shown. The diagrammatical representation which shows only three tubes is to be considered only as an example; the number of the tubes may vary at will.

Figs. 1 and 3 show the conditions for the case, in which the impulse is transmitted in response to the temperature of the superheated steam, the time at which the superheating begins being displaced towards the operating medium inlet point. In these views, short lines intersecting the tubes indicate flow control or throttling devices, the heavy short lines, at *t*, indicating a throttling or resistance setting of the devices and the light lines, at *o*, an open or non-throttling setting thereof.

Figs. 2 and 4 show the derivation of the impulse from a point lying at the end or near the end of the preheating, the end of the preheating being displaced with respect to the other tubes towards the generator outlet. Fig. 5 shows the derivation of the impulse in the case of a steam generator which is fed with an excess of water and in which the excess of water is separated from the steam in a drum as shown in the drawings. As before, the resistance or throttling set-

ting of the flow control devices is indicated in each instance by a heavy cross-line and by the reference character *t* and the non-throttling settings thereof are indicated by the light cross-lines and the reference character *o*.

In Figs. 6 and 7, there are shown diagrammatic arrangements employing the principle of control already described; and, in each of these views there are shown parallel connected tubes 10 and 11 supplied with feedwater by a pump 12 and with heat by means of any suitable combustion apparatus connected generally at 13. Superheated steam is supplied from the tubes to the prime mover 15.

15 The tubes 10 are so arranged and steam-producing media are so supplied thereto that the heating surface is divided into a preheating zone A, an evaporating zone B, and a superheating zone C; however, the measuring tube 11 is arranged, by any suitable means, to have its corresponding zones offset so as to provide regions of the heating surface thereof, preheating or superheating, overlapping or falling within the physical limits of the evaporation zone B, whereby such 20 overlapping portion of the measuring tube provides a region of variable temperature within the limits of the evaporation zone B and which may be used to give a temperature controlling impulse.

25 30 In Fig. 6, by restricting the flow, for example, in the measuring tube 11 relatively to the flow in each of the remaining tubes 10, it will be seen that the superheating zone C' extends further back so that the initial portion *b*—*c* falls within the physical limits of the main evaporation zone B of the tubes 10, and this initial or overlapping portion of the measuring tube is, therefore, subject to rise and fall of temperature dependent on 35 operating conditions and may be used to provide a temperature impulse for the controlling apparatus.

Any suitable means may be used to secure differential throttling of flow in the measuring tube with respect to the remaining tubes. Accordingly, in Fig. 6, the heavy cross-line 16 at the left hand end of the measuring tube indicates a greater resistance to flow therein than through the remaining tubes 10, the resistance of the latter being indicated by the relatively light cross-lines 17. In this view, a temperature responsive device 18 is shown associated with the overlapping portion *b*—*c* of the measuring tube and provides an impulse for the control system, as will be immediately pointed out.

55 Fig. 7 shows a diagrammatic arrangement which is similar to Fig. 6 except that the resistances are reversed, greater flow occurring through the measuring tube 11 than through the remaining tubes 10, with the result that the preheating, evaporation, and superheating zones A₂, B₂, and C₂ are displaced toward the outlet, whereby there is provided a final portion *a*—*b* of the preheating zone A₂ which overlaps the initial portion of the main evaporation zone B, this overlapping portion *a*—*b* of the measuring tube providing a region of heating surface whose temperature varies dependent upon operating conditions and which falls within the physical limits of the main evaporation zone. Accordingly, the 60 temperature responsive device 18' is associated with the overlapping portion *a*—*b* and provides a temperature impulse for the controlling system.

65 As hereinbefore pointed out, resistance or flow control devices are associated with the various tubes so as to secure a differential flow effect

in the measuring tube with respect to the remaining tubes, any suitable flow control or throttling devices being associated with the tubes for this purpose. In Figs. 1 to 7, inclusive, the throttling or resistance setting of these devices is indicated in each instance by a heavy cross-line and the reference character *t* and the non-throttling setting is indicated by a light cross-line *o*. Figs. 8 and 9 show, by way of example, flow control or throttling devices capable of being placed in the throttling position, *t*, or in the non-throttling or open position *o*. In these views, the resistance or throttling condition, *t*, is secured by adjusting the valve 22 so that flow occurs through the upper branch of the passage having the orifice 23 while the open or non-throttling condition is secured by adjustment of the valve so that flow occurs through the lower branch of the passage.

As hereinbefore described, the load effect of the prime mover may be used to supply a controlling impulse to either or both of the steam-producing media, feedwater and heat, supplied to the boiler. In Figs. 6 and 7, this impulse is indicated diagrammatically as originating with the prime mover governor and going to motors 19 and 20, which determine or control the operation of the feed pump and of the fuel and air supply. In addition, the temperature impulse coming from the device 18 in Fig. 6 is shown as being superimposed upon the main impulse in order to exercise a corrective effect, whereby a desired outgoing superheated steam temperature may be maintained. In Fig. 7, instead of the governor impulse being used to control both the feedwater and the heat supply means, this impulse is exerted only on the feed water supply means, the temperature responsive device 18' operating to control the fuel and air supply means. Accordingly, therefore, so far as the present invention is concerned, it is only essential that the control system shall use a temperature impulse and it is immaterial specifically how this impulse is utilized.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In a steam generator, a plurality of parallel-connected tubes, means for supplying feedwater as working medium and heat to the tubes so that the working medium is preheated, vaporized and superheated in successive zones; means providing for offsetting of said zones in one tube with respect to the zones of the remaining tubes, so that said first tube constitutes a measuring tube, whereby the measuring tube has a region of variable temperature which partially overlaps the evaporation zone of said remaining tubes; and means for deriving a temperature impulse from said overlapping region of the measuring tube and for utilizing the impulse to control said supply means.

2. The combination as claimed in claim 1 wherein the means providing for offsetting of the zones in the tubes are adjusted so that the initial portion of the superheating zone of the measuring tube is overlapped by the final portion of the evaporation zone of the remaining tubes and wherein the means for deriving a temperature

impulse from the measuring tube is associated with said overlapped portion thereof.

3. The combination as claimed in claim 1 wherein the means providing for offsetting the zones of the tubes are adjusted so that the final portion of the preheating zone of the measuring tube is overlapped by the initial portion of the

evaporation zone of the remaining tubes and wherein the means for deriving the temperature impulse from the measuring tube is associated with said final overlapped preheating portion thereof.

MARTIN EULE.
